[57] CLAIM

The ornamental design for an auxiliary rear view mirror for attachment to a vehicle exterior rear view mirror, as shown and described.

DESCRIPTION

FIG. 1 is a perspective view of the auxiliary rear view mirror for attachment to a vehicle exterior rear view mirror;

FIG. 2 is a perspective view thereof on a reduced scale attached to a vehicle exterior rear view mirror which is shown in broken lines for illustrative purposes only and forms no part of the claimed design;

FIG. 3 is a front elevational view thereof;

FIG. 4 is a top plan view thereof;

FIG. 5 is a rear elevational view thereof;

FIG. 6 is a bottom plan view thereof;

FIG. 7 is a left side elevational view thereof;

FIG. 8 is a right side elevational view thereof; and,

FIG. 9 is a sectional view thereof taken along line 9—9 in FIG. 3.
